(57) **CLAIM**

The ornamental design for a electrocardiography device, as shown and described.

DESCRIPTION

FIG. 1 is a perspective view showing my design;
FIG. 2 is a front elevational view thereof;
FIG. 3 is a rear elevational view thereof;
FIG. 4 is a right side elevational view thereof;
FIG. 5 is a left side elevational view thereof;
FIG. 6 is a top plan view thereof; and,
FIG. 7 is a bottom plan view thereof.
The broken lines in FIGS. 1 and 6 illustrate environmental subject matters. The dash-dot lines in FIGS. 3 and 7 illustrate portions of the electrocardiography device that form no part of the claimed design. None of the broken lines form a part of the claimed design.

1 Claim, 5 Drawing Sheets
